CLAIM

The ornamental design for a window, as shown and described.

DESCRIPTION

FIG. 1 is a front perspective view of a window in accordance with a first embodiment of the ornamental design of the present invention.

FIG. 2 is a rear perspective view thereof.

FIG. 3 is front elevation view thereof.

FIG. 4 is rear elevation view thereof.

FIG. 5 is a sectional view taken at line 5—5 of FIG. 3.

FIG. 6 is a sectional view taken at line 6—6 of FIG. 3.

FIG. 7 is a sectional view taken at line 7—7 of FIG. 3.

FIG. 8 is a front perspective view of a window in accordance with a second embodiment of the ornamental design of the present invention.

FIG. 9 is a rear perspective view thereof.

FIG. 10 is a front elevation view thereof.

FIG. 11 is a rear elevation view thereof.

FIG. 12 is a sectional view taken at line 12—12 of FIG. 10.

FIG. 13 is a sectional view taken at line 13—13 of FIG. 10; and,

FIG. 14 is a sectional view taken at line 14—14 of FIG. 10.

The broken lines in the figures are for illustrative purposes only and form no part of the claimed design.
